UNITED STATES PATENT OFFICE.

DUNCAN D. McBEAN, OF NEW YORK, N.Y.

LUMBER-SHIP.

1,277,003.

Specification of Letters Patent. Patented Aug. 27, 1918.

Application filed June 27, 1917. Serial No. 177,208.

To all whom it may concern:

Be it known that I, DUNCAN D. McBEAN, a citizen of the United States, residing at New York, in the county and State of New York, have invented certain new and useful Improvements in Lumber-Ships, of which the following is a full, clear, and exact description.

Attempts have been made to make sea going rafts of timber and lumber, but they have usually proved to be failures through making them more or less flexible, instead of uniting them, so as to form a rigid body. It is impossible to associate them into a sufficiently flexible structure so that they will adjust themselves to the forms of the undulations of the waves, consequently the movement in their joints is a weakness in them which soon causes their destruction.

This invention resides in a new means of transporting lumber and timber over water routes, without the use of the ordinary means of transportation such as the ships or barges which are now built and used for that purpose.

This invention consists in building up in or on the water a cargo of timber and lumber and assembling it into a rigid body having the form of the hull of a ship, in which all the space within it is filled solid with lumber and timber, except where waterproofed spaces within it are required above the bottom tier of timber forming the bottom of the hull. This ship may be propelled by the use of machinery or by the use of sails as in an ordinary ship, or by the use of both.

In carrying out this invention I construct the timber ship in the manner which is more specifically herein described, but this description, as will be understood is of a specific embodiment of the broader idea.

The specific manner in which I prefer to carry out the invention is illustrated in the accompanying drawings in which:

Figure 1 is a longitudinal section along the center line of portions of the forepart and afterpart of the hull of the ship.

Fig. 2 is a cross-section of the hull at or about midship.

Fig. 3 is a longitudinal section along the sides showing a portion of one side of the hull.

Fig. 4 is a plan showing the preferred form for placing the tiers of timber forming the bottom of the hull.

Following in some detail the proposed plan of construction I first assemble on the surface of a convenient body of water, courses of rather heavy timbers forming a tier A. I unite the keel timber K to the center pieces of tier A by bolts *a*. Then I lay on top of tier A, a certain number of the transverse tier of timbers B, bolting one end of the latter to the outside course of timber in tier A by bolts *b*. By any suitable means the corners of timber forming tier A are then forced firmly together in a level tier, and the opposite ends of the superimposed timbers are secured by bolts *c* to the opposite outer timber in tier A.

Upon tier A, I then place upright side timbers C, and a center line of upright timbers D, securing by bolts *d* through the lower ends thereof to the transverse timbers in tier B, and the outside uprights are bolted also to the outside planking E.

At this stage, I also place at suitable intervals upright timbers along the center line to serve as masts F. The height of the side upright timbers is such that they will extend above the contemplated deck G of the ship, sufficiently to constitute supports for the bulwarks and rail H; that of the center upright timbers D, such as to permit of longitudinal timbers I, above the deck to be secured to them, and the portion of the mast timbers above the deck are to be rounded or dressed to permit of their proper use with tackle and sails.

After the upright timbers are placed and fastened in the manner described, the second tier of bottom timbers is completed by filling in the spaces between the timbers B with others of the same thickness, and planking E is secured to the outside of the said uprights. A third tier of longitudinal bottom timbers J is then laid on and transversely to those of the second tier.

Generally three tiers of bottom timbers are ample for a large ship. The ends of the timbers of the second tier may all be bolted to the lower and superimposed tier of timbers, or only a portion of them as may be found necessary and desirable. When the second tier timbers B are in contact with the center uprights D and masts F they may be secured by bolts *d* to the latter, and the longitudinal timbers alongside the said uprights and masts should be held together by bolts *e* that pass through the latter.

The lengths of the pieces of timber placed

longitudinally, and forming the courses of the third tier of timbers J are made longer or shorter than those below them in the first or bottom longitudinal tier of timbers A.

- 5 All the ends of timbers in the bottom tier are held by bolts *f* to the timber above it in the third tier, and all the ends of the timbers forming the third tier are bolted to the timbers below them in the first tier. The 10 courses of timber which lie adjacent to the center upright timbers in the fourth course are not only bolted to the center upright timbers but are also secured by bolts *i* to the keel piece under the first tier, and those 15 lying adjacent to the side upright timbers are fastened by bolts *j* to the outside courses of timbers on the outside of the first tier, thus breaking joints and bolting the bottom four courses and keel together and tying 20 them to the upright timbers. The courses of timber placed longitudinally forming the first and third tiers of timbers in the bottom are made longer or shorter than their neighbors at their sides, thus toothing the courses 25 and breaking joints horizontally across each tier. In some cases it may be desirable to have the bottom tier started with a transverse tier instead of a longitudinal tier as shown in Fig. 2, then reversing the order 30 of laying the first four tiers of timbers in the hull.

It is preferred to have all timbers, except those in the lower courses, that are bolted to the upright timbers, clamped or forced 35 down hard on the timber and lumber underlying them before bolting them so as to prevent looseness in the joints and secure rigidity to the structure.

After the three tiers of bottom timbers 40 are laid, transverse timbers L (see Figs. 2 and 3) are laid upon them and carried entirely across the structure from the side planking on one side to that on the other, and their ends are fastened to the side uprights and also to the center uprights by 45 bolts and plates *g*.

On top of tier L longitudinal planks are spikied to the inside of the side upright timbers C and to each side of the center upright timbers D. The longitudinal spaces N 50 between the upright timbers and between the rows of planking spikied to them are filled solid with timber as the planking is built up.

55 The timbers and lumber constituting the cargo are then stowed on the bottom tiers between the walls of planking M, thus forming the body of the hull of the ship. As the cargo timbers are placed between the 60 walls of planking M it is laid, preferably, in tiers of even thickness, and so as to break joints and interlock as far as possible.

When a pile of timber or lumber of the desired thickness has thus been stowed, 65 cross-timbers G, extending entirely across

the ship are secured to the side uprights and secured by bolts *h* to those in the center, which tie the ship together and bond the cargo to the tier of bottom timbers.

In this way the hull of the ship is built 70 up to the level of what is intended to be the deck, where the final tier of cross timbers G is secured in place. Along the entire length of the deck heavy longitudinal timbers I are then laid against both the side and center 75 uprights and firmly secured by bolts *k* thereto. The projecting side uprights are planked on the outside to form the bulwarks and rail H.

In the construction of the hull of the ship, 80 such keel as may be necessary is built on or formed with the under tier of timbers, and such of the central longitudinal timbers as may be necessary are caused to project at the stern to form supports or bearings for a 85 rudder post. The bow and stern may be formed of any desirable shape.

As intimated above, a bowsprit, if necessary, is built in with the cargo, and such shrouds, stays, sails and the like, with 90 means, when desired for working the latter, are added. On the deck, houses may be built for the crew, for the necessary engines, for supplies and the like of a suitable number and capacity.

95 Should it be desired, any portions of the structure may be left as empty compartments, in which case the walls thereof must be made water-tight, or the entire ship may be made water-tight by the use of courses 100 or tiers of water-proofing character of any suitable nature.

With the details of this and other like features, the present application is not particularly concerned as they are matters that 105 those skilled in this art may adopt and use without the exercise of invention. My main purpose as indicated by the context is to transfer large cargoes of timber and lumber over water routes with displacements 110 only sufficient to float them, by assembling each cargo, on the water, into the form and outlines of the hull of an ordinary ship that is filled solid with a cargo of timber and lumber, which may be propelled by the use 115 of machinery, or as a sailing ship, or by the use of both, thus avoiding the building of the hull of the ship or any part of it on shore and launching it, thereby saving a

large expense, and permitting the hull to 120 be made far more rigid than is practicable by the usual method of building hulls of ships, thus enabling the assembling of a cargo of lumber into the form and outlines of the hull of a ship at a cost not much 125 more than that of the loading of it into the several ordinary ships that are necessary to carry the large cargo, and a saving of time. Its transportation risk is limited to the loss of the cargo without the additional risk of 130

the loss of the several ordinary ships carrying it. The damage to it by a torpedo hitting it, if any, would be insignificant in comparison to what it would be to the ordinary ships carrying the cargo. The large outlay of capital represented by the several ordinary ships necessary to carry the cargo is avoided. A saving is made of the cost of the expenditure of power necessary to 10 propel the weight of the extra displacement of the ordinary ships above that required to float only the cargoes of lumber and timber within them. The delivery of the cargo is practicable to be made immediately on its 15 arrival in the harbor of its destination, instead of having to wait to unload it. It may be unloaded at a less cost than that of unloading it from ordinary ships, and without incurring the cost of demurrage 20 usually paid to ships for delays in unloading their cargoes.

What I claim as my invention and desire to secure by Letters Patent is:

1. A timber ship by means of which lumber and timber in quantity may be transported by water, composed of a cargo of such lumber and timber assembled in a series of transversely laid tiers and temporarily secured entirely by its own members 30 in a substantially solid raft having the lines of a ship which permit it to be propelled by machinery or in any wind by sails, and which is adapted in unloading to be completely dismembered, to utilize all 35 of the lumber and timber used in its construction.

2. The method herein described of associating for the purpose of transportation by water, a cargo of lumber or timber, which 40 consists in assembling such cargo on the water, laying together therein tiers of the same to form the bottom of a substantially solid mass, building up from such bottom by means of upright timbers the frames for 45 the sides and ends, filling the interior progressively from the bottom as the structure sinks, and tying, binding and bracing the structure by means of the timbers and planking laid transversely in tiers and temporarily fastening devices securing the same 50 where necessary.

3. The method herein described of associ-

ating for the purpose of transportation by water a cargo of lumber and timber, which 55 consists in assembling the cargo, associating on the water and securing together while floating a plurality of tiers or courses of timber to form a bottom, erecting uprights along the side and central lines of the bottom, applying side walls of planking to 60 such uprights, tying together the structure by means of such uprights and longitudinal and transverse timber, while progressively building up into a substantially solid mass the entire cargo with all its members capable 65 of being dissociated and used.

4. The timber and lumber ship herein described comprising a plurality of bottom tiers of timbers, the alternate tiers being laid at right angles to each other, 70 and all securely fastened together, side and center line uprights resting on and secured to the bottom timbers, planking walls secured to the uprights, forming side and center keelsons throughout the hull 75 above the tiers of timber forming the bottom of the ship, and longitudinal and transverse tying and bonding timbers between and alongside the upright timbers.

5. The timber and lumber ship herein described, comprising a plurality of oppositely laid tiers of bottom timbers, secured together, side and center line uprights resting on and secured to such bottom tiers, 80 walls of planking secured to the uprights, 85 cargo lumber stowed solidly between such walls and transverse and longitudinal timbers secured to the uprights for tying and bonding together the several portions of the hull of the ship.

6. The timber and lumber ship herein described, comprising a plurality of oppositely laid tiers of bottom timbers, secured together, side and center line uprights, resting on and secured to such bottom tiers at 95 intervals, walls of planking secured to the uprights, cargo lumber stowed solidly between such walls, transverse and longitudinal timbers secured to the uprights for tying and bonding together the several portions of the hull of the ship.

In testimony whereof I hereunto affix my signature.

DUNCAN D. McBEAN.
